UNITED STATES PATENT OFFICE

WILHELM ULRICH, OF KIEL, GERMANY, ASSIGNOR TO DEUTSCHE WERKE KIEL AKTIENGESELLSCHAFT, OF KIEL, GERMANY, A CORPORATION OF GERMANY

TWO-STROKE INTERNAL-COMBUSTION ENGINE

Application filed January 11, 1928, Serial No. 246,051, and in Germany December 19, 1924.

The invention concerns the scavenging of two-stroke internal combustion engines with inlet and exhaust ports controlled by the piston.

Before giving the characteristics of the invention, the main kinds of known scavenging processes will be explained.

With cross scavenging the inlet ports are arranged only on one side of the cylinder and the outlet ports on the opposite side in substantially the same plane. The scavenging air is introduced into the cylinder in such manner that it rises up the wall of the cylinder above the inlet port. It is deflected by the cover and then flows down over the opposite side of the cylinder to the outlet port.

The lateral reversing scavenging is characterized by the fact that the inlet and outlet ports are arranged in two planes one above the other. The scavenging air is guided up the cylinder wall opposite to the inlet ports and not perforated by outlet ports and after deflection at the cylinder cover flows down over the opposite wall to the outlet ports disposed above the inlet ports.

With central reversing scavenging the scavenging air enters through ports arranged around the whole periphery of the cylinder, rises up in the longitudinal axis of the cylinder, is deflected at the cylinder cover and flows around the cylinder wall to outlet ports similarly arranged over the whole circumference of the cylinder above the inlet ports (Fig. 1).

The central reversing scavenging has the advantage over cross scavenging and lateral reversing scavenging, that the inlet and outlet ports can be arranged around the whole circumference of the cylinder so that for admission and exhaust a greater total cross sectional area is available with relatively little lost stroke. With the other scavenging processes on the other hand the cylinder wall above the inlet ports is required for guiding the scavenging air and may therefore not be interrupted, at least not over the whole periphery, by outlet ports. Consequently with the central reversing scavenging for the same quantity of air a lesser height of port is neces-

sary than with these other scavenging processes and there is therefore a reduction in lost piston stroke and overall height of the engine, or with a similar height of port a lower pressure of scavenging air and a saving in work of compression and therewith an improved efficiency of the engine is attained.

The other scavenging processes have moreover the disadvantage that on account of the impossibility of distributing the ports uniformly around the whole circumference unequal temperature stresses occur in the cylinder, which with strong heating in operation readily lead to faults or fracture.

Finally the distribution of the outlet ports around the whole cylinder circumference with the central reversing scavenging has the further advantage of a rapid expansion of the exhaust gases.

The central reversing scavenging would therefore have the preference over the other scavenging processes if it did not have the disadvantage that the scavenging stream rising in the cylinder, as practice has shown, is not stable, but oscillates to and fro whereby eddies are set up which unfavorably effect the scavenging.

The present invention solves the problem of obviating this disadvantage of central reversing scavenging, in that the streams of air entering the cylinder are influenced by the irregularity in the introduction of the air in such manner that the combined current of air rises at an inclination to the cylinder axis and retains this direction. The rising air stream is thus stabilized so that the striking action of the scavenging stream and the formation of eddies is avoided.

The irregular form of the means serving to introduce the air is so designed that on the one hand the streamlets contact on opposite sides so that premature escape of the scavenging air through the outlet ports is prevented, and on the other hand however it is assured that the combined stream rises in the cylinder in a definite constant inclined direction.

In this way the advantages of the arrangement of ports in the central reversing

scavenging are combined with those of a stable flow of the stream.

The accompanying drawings illustrate at Fig. 1 a longitudinal section of a cylinder constructed according to the invention; Fig. 2 a cross section along the line $s-s$ of Fig. 1 and Fig. 3 a longitudinal section with a modified form of piston.

a indicates the cylinder, *b* the piston situated at the lower dead centre. The ports *c* for the admission of scavenging air and the port *d* for the exhaust thereof are arranged radially and distributed around the whole circumference of the cylinder.

In the constructional example according to Figs. 1 and 2 the irregularity of the air conduits necessary for stabilizing the air stream is effected by arranging the supply and exhaust channels for the scavenging air unsymmetrically of the cylinder axis. In consequence of this the air pressure of the streamlets entering through the ports into the cylinder is so graduated that a continual excess pressure of the streamlets entering on one side of the cylinder over those entering the opposite side is produced. The combined stream of scavenging air rising in the cylinder is thereby diverted from the longitudinal axis of the cylinder and towards the weaker portions of the stream. The rising stream is inclined to the cylinder axis towards the cover and constantly retains this direction. It is deflected at the cover and then again disperses into streamlets which flow down on all sides to the exhaust ports. The premature exhaust of the stronger streamlets through the exhaust ports is prevented by the weaker streamlets. Contrary to the lateral reversing scavenging no closed cylinder wall is necessary here for guiding the rising scavenging stream; the latter guides itself.

The stabilizing of the flow of the stream can be assisted by the unsymmetrical form of the top of the piston as illustrated in Figure 3 of the drawings.

The invention is suitable for constant pressure as well as for constant volume combustion engines.

I claim:—

1. In a two stroke internal combustion engine, a cylinder, a piston in said cylinder, a plurality of annular scavenging air ports in said cylinder, a plurality of annular exhaust ports in said cylinder in a plane above said intake ports, a baffle on said piston, said baffle being disposed unsymmetrically of the cylinder axis, by which said scavenging air rises in the cylinder obliquely to the axis of the latter.

2. In a two stroke internal combustion engine, a cylinder, a piston in said cylinder, a plurality of annular scavenging air ports in said cylinder, a plurality of annular exhaust ports in said cylinder in a plane above said intake ports, an air supply channel surround-

ing said intake ports, said channel being disposed unsymmetrically of the cylinder axis, a baffle on said piston, said baffle being disposed unsymmetrically of the cylinder axis, by which unsymmetrical disposition of said air supply channel and of said piston baffle said scavenging air rises in the cylinder obliquely to the axis of the latter.

WILHELM ULRICH.
